UNITED STATES PATENT OFFICE.

JOHN W. GUNNELS AND DAYTON O. SHIVES, OF HANCOCK, MARYLAND.

MOWER.

SPECIFICATION forming part of Letters Patent No. 228,890, dated June 15, 1880.

Application filed February 4, 1880.

To all whom it may concern:

Be it known that we, JOHN W. GUNNELS and DAYTON O. SHIVES, of Hancock, in the county of Washington and State of Maryland, 5 have invented certain Improvements in Mowing-Machines, of which the following is a specification.

This invention relates to improvements in mowing and reaping machines, whereby the 10 frame carrying the drag-bar and the cutter-bar or knife-bar may be elevated or lowered at pleasure, and also the knife-bar elevated at such an angle that the machine may be run nearer to a standing tree, stump, or other obstacle 15 too high for the frame to pass over, all of which will be hereinafter more fully described, and set forth in the claim.

Figure 1 is a plan view of the whole machine, having a part of the seat-platform broken 20 away to show the clutch devices below. Fig. 2 is an end elevation, showing the knife-bar elevated to pass an obstacle. Fig. 3 is also an end elevation, showing the drag-bar elevated to pass over an irregularity in the surface of 25 the ground.

The frame A is of the ordinary construction and mounted on two wheels, B B, on the axle C of which wheels is a beveled-cog driving-wheel, (not shown in the drawings,) and which 30 wheel, when not in action, turns loosely on the axle; but by means of the clutch C' (shown in Fig. 1) the driving-wheel turns with the axle, and by meshing with a pinion on a transverse shaft, D, the end of which is seen in Figs. 2 35 and 3, the cam-wheel D' is carried around with the shaft D, which cam-wheel D' has within its face six recurvatures, d' d', &c., so that the wrist-pin a of the crank-lever b, in traveling in the recurved grooves d' d', will have an up-and-down motion twelve times to every revolution of the wheel D'. In Fig. 2 the wrist-pin a is down, and in Fig. 3 it is up. Consequently the crank-lever b and its connecting-rod c, which is pivoted to b at c', will reciprocate 40 back and forward twelve times, also carrying the knife-bar and blades d d d, which are attached to the knife-bar in the usual manner.

The crank-lever b is pivoted at b' to a standard, a'', on the main frame A of the machine. 45 The finger-bar e and knives d d d are of the usual construction, and require no description.

A' is the drag-bar, and on it is the shoe E, the end of which is seen in Figs. 2 and 3. The shoe E turns freely on the drag-bar A', and to the shoe is firmly attached the knife-bar and 55 knives, so that when the shoe is turned on the drag-bar A' the knife-bar and knives are elevated also. At e' the shoe E has a segment-rack, the teeth of which mesh with the teeth of a rack-lever, f, which is pivoted to the bar 60 A'' at f''. This lever f has a shoulder, f'', the purpose of which is to bear against and act as an abutment for the shoe E, as seen in Fig. 3 at f'', when the bar A'' is elevated, and with it the finger-bar e, as shown in Fig. 3, to pass 65 over the rock z and raise the knives. Bar A'' is shown in solid lines in Fig. 1 and in dotted lines in Figs. 2 and 3.

On the end of lever f is fastened a chain, g, (shown in Fig. 2,) which passes over a pulley, h, 70 on the end of a rock-shaft, h'. At the other end of rock-shaft h' is a ratchet-wheel, h'', having a lever-arm, i, and a spring-pawl, i'. In Fig. 2 the lever-arm i is carried to the left hand, whereby the rock-shaft h' and pulley h 75 are rotated, and the chain g elevates the arm of lever f, the teeth of which cause the shoe E to rotate in the opposite direction, and thereby elevate the knife-bar and knives, as seen in the figure, to pass an elevated obstacle, thus 80 saving the distance between the numbers 1 and 2 each side of that obstacle.

The rock-shaft h' and pulley h have another function, which is to elevate the drag-bar A', and with it the knife-bar and knives, as follows: A chain, g', is wound around pulley h on the opposite side to the chain g, as seen in Fig. 3. The lower end of chain g' is attached to the bar A'', and whenever any obstacle on the ground, such as a rock or low stump, has 90 to be passed over, the operator, who sits on the platform F, (no seat being represented in the figures,) turns the lever-arm i to the right, as seen in Fig. 3, whereby the chain g' is wound over pulley h, and the bar A'' is thereby lifted, 95 and with it the shoe E and finger-bar e. Shoe E is sustained against the shoulder of lever f at f'', as before explained, and this elevation of all these parts is only limited by the extent to which the lever i can be turned to 100 the right always enough for the knives to pass over any ordinary rock or low stump. Should

either range higher, then the first operation must be resorted to.

At G, Fig. 1, is seen a lever by which the clutch C' is to be operated. The lever is bent, 5 as seen in broken lines, and is connected to the clutch, and when turned down, as shown, the clutch is engaged with the wheel at C''; but to uncouple, the operator pulls the lever G into the vertical position shown in the dotted circle at G'. The lever passes along the edge of an inclined cam-surface, k, and consequently the lever is moved laterally, and carries with it the clutch C', which is pulled out of gear from e' to the dotted lines in Fig. 1. 15 The spring h' is then recoiled, and when the

lever G is again thrown into the first position the clutch C' comes into gear again.

We claim—

In a mowing-machine, in combination with the finger-bar and appurtenances, the lever i, 20 the pulley and shaft h h', chains g g', brace-bar A'', lever f, provided with a broad bearing, f'', and shoe E, provided with cogs corresponding with the cogs on lever f, substantially as and for the purpose described.

JOHN W. GUNNELS.
